UNITED STATES PATENT OFFICE.

LOVELL H. PAGE, OF HAMDEN, CONNECTICUT.

EXTRACTOR MECHANISM FOR BOLT-ACTION FIREARMS.

Application filed March 28, 1927. Serial No. 178,868.

This invention relates to improvement in extractor mechanisms for bolt-action firearms and has for its object the production of a simple, reliable and rugged mechanism 5 of the class described.

A further object of this invention is to provide an extractor mechanism which may be readily installed and removed from the firearm.

10 With these objects in view, my invention consists in an extractor mechanism for bolt-action firearms characterized by an extractor-bar provided near its rear end with a laterally-projecting locking-lug; a bolt provided with a longitudinal chamber for the reception of the extractor-bar and with a laterally-extending passage intersecting the said chamber for the reception of the said locking-lug; and a spring for normally 20 holding the said locking-lug in the said locking-passage.

My invention further consists in an extractor mechanism for bolt-action firearms characterized as above and having certain 25 other details of construction and combinations of parts as will be hereinafter described and particularly recited in the claims.

In the accompanying drawings:

30 Fig. 1 is a broken view in side elevation of the forward end of a bolt provided with my improved extractor mechanism;

Fig. 2 is a view thereof in front end elevation;

35 Fig. 3 is a transverse sectional view on the line 3—3 of Fig. 1;

Fig. 4 is a top or plan view of one of the extractor-bars;

Fig. 5 is a view thereof in side elevation; 40 and

Fig. 6 is an enlarged broken view in horizontal section showing the bolt, receiver, and gun-barrel of a firearm provided with an extractor mechanism embodying my invention.

In the embodiment of my invention herein shown, I employ a pair of substantially-cylindrical corresponding complementary extractor-bars 10 having their forward ends beveled as at 11 and each provided upon its inner face with a notch 12 for engaging the rim 13 of a cartridge 14, which, as usual, is located in the bore 15 of the gun-barrel 16.

As is the ordinary practice, the gun-barrel 55 16 is threaded into the internally-threaded

forward end of the receiver 17, as shown in Fig. 6.

The inner face of each extractor-bar is cut away to form a clearance-notch 18 which provides a flat bearing surface for a helical spring 19. The rear end of the outer face of each of the extractor-bars is also formed with a notch 20 which results in the formation of a fulcrum-shoulder 21, the function of which will hereinafter appear, 60 and also provides a flat seat for a laterally-projecting locking-lug 22 which is provided with a short shank 23 projecting through a lateral bore 24 in the rear end of each extractor-bar where it is riveted over as at 25, 70 so that the locking-lug virtually becomes a part of the extractor-bar to which it is attached.

The bolt 26 is of the ordinary type and, as shown, is provided on opposite sides of 75 its vertical center with two longitudinally-arranged extractor-chambers 27 and 28, the outer wall of each of which is intersected at its rear end by a locking-passage 29, while the inner wall thereof is intersected 80 by a transversely-arranged spring-chamber 30 extending between the said extractor-chambers and arranged in line with the locking-passages 29 aforesaid.

In assembling the extractor-bars 10 in the 85 bolt 26, I first insert one of them through the front end of either one of the extractor-chambers 27 or 28 until its locking-lug 22 is in line with one of the locking-passages 29. The spring 19 is now inserted into the 90 spring-chamber 30 through the opposite locking-passage 29 and compressed by a suitable tool, after which the complementary extractor-bar is inserted rearward through the forward end of the opposite extractor-chamber until its locking-lug 22 is 95 in line with the locking-passage 29 of the chamber in question.

As thus installed, the single spring 19 serves to hold the locking-lugs 22 of the respective extractor-bars in the respective locking-passages 29 and permits the outer ends of the respective extractor-bars to swing outward upon their fulcrum-shoulders 21, as may be required to permit the notches 12 105 to be engaged with and disengaged from the rim 13 of the cartridge 14.

Should it be necessary for any reason whatever to remove the extractor-bars from the bolt, it is only necessary to force one of 110

the locking-lugs 22 inward to clear it from its locking-passage 29 and then draw the extractor-bar, of which it forms a part, forward and out through the open forward end 5 of the particular extractor-chamber in which the extractor-bar is housed. The removal of this extractor-bar as just described will permit the spring 19 to be removed laterally outward through the locking-passage 29 10 just vacated, after which the remaining locking-bar may be readily removed by disengaging its locking-lug from its adjacent locking-passage 29 and in turn drawing it outward through the forward end of the 15 other longitudinal extractor-chamber.

I claim:

1. The combination with the bolt of a bolt-action firearm; of two longitudinally-extending extractor-chambers respectively 20 formed on the opposite sides of the center of the said bolt; a transverse locking-passage intersecting each of the said extractor-chambers near the rear ends thereof; two extractor-bars housed in the said extractor-chambers respectively with capacity for 25 rocking-movement; a transversely-offsetting locking-lug located near the rear end of each of the said extractor-bars; and a spring impinging at its opposite ends against the said 30 extractor-bars respectively for yieldingly holding the said locking-lugs in the said locking-passages.
2. The combination with the bolt of a bolt-action firearm; of two longitudinally-extending extractor-chambers respectively 35 formed on the opposite sides of the center of the said bolt; a transverse locking-passage intersecting each of the said extractor-chambers near the rear end thereof; a 40 spring-chamber formed in the said bolt in line with the said locking-passages; two extractor-bars housed in the said extractor-chambers respectively, with capacity for 45 rocking movement; a transversely-offsetting locking-lug near the rear end of each of the said extractor-bars; a spring-chamber formed in the said bolt in line with the said

locking-passages; and a spring located in the said spring-chamber and adapted to impinge at its opposite ends against the said 50 extractor-bars for holding the said locking-lugs in the said locking-passages.

3. The combination with the bolt of a bolt-action firearm; of two longitudinally-extending extractor-chambers respectively 55 formed on the opposite sides of the center of the said bolt; a transverse locking-passage intersecting each of the said extractor-chambers near the rear ends thereof; two extractor-bars housed in the said extractor-chambers respectively with capacity for 60 rocking movement; a fulcrum-shoulder formed upon each of the said extractor-bars; a transversely-offsetting locking-lug located near the rear end of each of the said extractor-bars; and a spring impinging at its opposite ends against the said extractor-bars respectively for yieldingly holding the said locking-lugs in the said locking-passages.

4. The combination with the bolt of a bolt-action firearm; of two longitudinally-extending extractor-chambers respectively 70 formed on the opposite sides of the center of the said bolt; a transverse locking-passage intersecting each of the said extractor-chambers near the rear ends thereof; a spring-chamber formed in the said bolt axially in 75 line with the said locking-passages; two extractor-bars housed in the said extractor-chambers respectively with capacity for 80 rocking movement; a fulcrum-shoulder formed upon each of the said extractor-bars; a transversely-offsetting locking-lug located near the rear end of each of the said extractor-bars; and a spring located in the 85 aforesaid spring-chamber and impinging at its opposite ends against the said extractor-bars respectively for yieldingly holding the said locking-lugs in the said locking-passages.

In testimony whereof, I have signed this specification.

LOVELL H. PAGE.
